UNITED STATES PATENT OFFICE.

GEORGE MICKOW, OF CHICAGO, ILLINOIS.

PUZZLE.

SPECIFICATION forming part of Letters Patent No. 425,041, dated April 8, 1890.

Application filed May 1, 1889. Serial No. 309,281. (No model.)

To all whom it may concern:

Be it known that I, GEORGE MICKOW, a citizen of the United States, and a resident of Chicago, in the State of Illinois, have invented 5 a certain new and useful Improvement in Puzzles; and I do hereby declare the following to be a full, clear, and exact description of the same, reference being had to the accompanying drawings, in which—

10 Figure 1 is a plan view of my improved appliance; Fig. 2, a vertical section of the same; Fig. 3, a plan view of a modified form of the appliance.

Similar letters of reference indicate like 15 parts in the several views.

This invention relates to that type of puzzles in which a set of marbles are placed within a box provided with pockets and the box manipulated in the hands of the operator so 20 that the different marbles will be introduced into the respective pockets and occupy the same singly; and the present improvement has for its object to provide a simple and convenient form of such appliance possessing the 25 necessary difficulty of achievement.

Referring to the drawings, A represents an open-top box of either a square shape, as represented in Fig. 1, or a circular shape, as represented in Fig. 3. Pockets or chambers 30 B, four in number, are arranged at the corners of the box A when the same is of a square shape, or equidistant apart around the rim of the box when of a circular shape, as represented in Fig. 3. These pockets or chambers 35 are formed by curved vertically-arranged walls, as shown, in which are formed entrance-openings b, located on lines radial from the

center of the box A and forming a passage-way into such pockets or chambers.

C is a central depression in the center of 40 the box-bottom, to receive and aid in holding the proper marble when the same has been manipulated into its proper position, and b' are similar depressions within the pockets B, for a like purpose.

45 D represents a series of five marbles, four of a single color and one of an odd or different color. These marbles are intended to represent cats, the object being to play a game entitled "Pussy wants a corner" by so manipulating the box as to secure one of even-colored marbles in each of the pockets B and the odd-colored marble in the central depression C.

Having thus fully described my said invention, what I claim as new, and desire to secure by Letters Patent, is—

A toy or puzzle adapted to be held in the hand, comprising a box having a continuous wall, a central depression C, a series of marginal equidistant pockets or chambers B, having openings b, located on lines radial from the center of the box A, and depressions b' within said pockets or chambers, in combination with a set of four marbles of a similar 60 color and one marble of an odd color, essentially as herein described.

Witness my hand this 8th day of April, 1889.

GEORGE MICKOW.

In presence of—

ROBERT BURNS,
EDWD. A. WEBSTER.
